(**) Term: **14 Years**

CLAIM

(21) Appl. No.: **29/136,154**

The ornamental design for a folding, swivel-back wheeled chair, as shown and described.

(22) Filed: **Jan. 29, 2001**

DESCRIPTION

(51) LOC (7) Cl. **06-01**

FIG. 1 is a perspective view of a folding, swivel-back wheeled chair showing my new design.

(52) U.S. Cl. **D6/368**

FIG. 2 is a left side elevational view thereof, the right side being a mirror image thereof;

(58) Field of Search D6/334, 335, 368,

FIG. 3 is a front elevational view thereof;

D6/374, 376, 380, 500, 501, 502; 297/16.1,

FIG. 4 is a rear elevational view thereof;

34, 55, 56, 57, 58, 59, 452.1

FIG. 5 is a top plan view thereof; and,

D6/368

FIG. 6 is a bottom plan view thereof.

The fragmented line shading shown on the seat and backrest of the chair is understood to repeat uniformly throughout the circumscribed area.
